UNITED STATES PATENT OFFICE.

FREDERICK E. KOHLER, OF CANTON, OHIO.

DESIGN FOR A HANDLE FOR CAN-OPENERS.

SPECIFICATION forming part of Design No. 22,533, dated June 13, 1893.

Application filed April 13, 1893. Serial No. 470,253. Term of patent 7 years.

To all whom it may concern:

Be it known that I, FREDERICK E. KOHLER, a citizen of the United States, and a resident of Canton, county of Stark, State of Ohio, have 5 invented and produced a new and original Design for Handles for Can-Openers, of which the following is a full, clear, and exact description, reference being had to the accompanying drawing, making part of this specification.

My invention or production relates to a novel design for handles for can openers, the leading feature of which consists in the handle provided at each end with webs and opening, and with outwardly extending flanges at the edges of the webs, as will hereinafter more fully appear.

The accompanying drawing represents a perspective of a can opener showing my design.

In the said drawing the reference numeral 1 designates the handle, having its front end curved as seen at 2, and recessed as seen at 3

forming a web 4 with an outwardly extending flange 5 formed around the edge. The web 25 is formed with an elongated opening 6 and a semi-circular opening 7. The opposite end of the handle is rounded as shown, and one side is recessed as seen at 8 forming a web 9, having a hole 10 therein and the out-projecting flanges 11. This recessed portion extends from the end to about the middle of the handle and its contour is the same as the edge of the handle.

A can opener handle as shown and described 35 presents a very attractive appearance, highly pleasing to the eye.

What I claim is—

The design for a can opener handle herein shown and described.

In testimony whereof I have hereunto set my hand this 29th day of March, A.D. 1893.

FREDERICK E. KOHLER.
